TREE HOUSE DISPLAY CASE

Robert L. Williams, Edina, Minn., assignor to Village Bath Products, Inc., Minnetonka, Minn.

Filed Apr. 30, 1975, Ser. No. 573,039

Term of patent 14 years

Int. Cl. D70—02

U.S. Cl. D6—29

FIG. 1

FIG. 2

FIG. 3

FIG. 4

FIG. 5

FIG. 1 is a view in perspective of the front and one side of a tree house display case showing my new design;

FIG. 2 is a view in side elevation thereof showing the side opposite that shown in FIG. 1;

FIG. 3 is a view in rear elevation thereof;

FIG. 4 is a view in top plan thereof; and

FIG. 5 is a view in bottom plan thereof.

I claim:

The ornamental design for a tree house display case, substantially as shown.
